Application November 10, 1939, Serial No. 88,189

Term of patent 3½ years

To all whom it may concern:

Be it known that I, William Skolnick, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

The characteristic feature of my design resides in the combination on the princess dress disclosed of the specific buckle closures arranged on the center front in association with the contrastingly colored underskirt as shown.

I claim:

The ornamental design for a dress, substantially as shown and described.

WILLIAM SKOLNICK.
